UNITED STATES PATENT OFFICE.

FRANK B. FRETTER AND STARLEY F. BEASLEY, OF CLEVELAND, OHIO; SAID BEASLEY
ASSIGNOR TO SAID FRETTER.

ATOMIZER FOR LUBRICATING PURPOSES.

1,055,159.

Specification of Letters Patent.

Patented Mar. 4, 1913.

Application filed September 4, 1912. Serial No. 718,490.

To all whom it may concern:

Be it known that we, FRANK B. FRETTER and STARLEY F. BEASLEY, citizens of the United States, residing at Cleveland, in the county of Cuyahoga and State of Ohio, have invented certain new and useful Improvements in Atomizers for Lubricating Purposes, of which the following is a specification.

10 This invention relates to a new and original atomizer designed more especially to be used with what are known as sight feed lubricators, and the invention consists in the construction and combination of parts substantially as shown and described and particularly pointed out in the claims.

20 In the accompanying drawings, Figure 1 is a side elevation of a lubricator, a steam pipe and the atomizer exposed in said pipe and having its supply connection with the lubricator. Fig. 2 is a side elevation of the atomizer considerably enlarged as compared with Fig. 1, and Fig. 3 is a central sectional elevation thereof.

25 The novelty herein lies, first and chiefly, in the atomizer *a* as a new article of manufacture and sale and adapted to be used in conjunction with a suitable lubricator *b* or like source of supply, the said atomizer being located in the steam pipe *c*. A pipe line 2 leads from the pipe *c* to the lubricator and has a valve 3 in the angle thereof to control the flow of steam through the same, and a pipe 4 leads from the lubricator into pipe *c* 35 and is adapted to supply oil to the top of the atomizer through an elbow 5. The said elbow or joint 5 screws upon the neck 6 of the atomizer and the said neck is tubular while the body of the atomizer is shown as 40 solid, and the said neck has an orifice or hole 7 in its bottom through which the oil passes onto the spiral or worm 8. The said spiral runs about the outside of the body of the atomizer and is characterized by an 45 approximately concavo-convex formation in cross section, the channel in the top thereof being substantially trough-shaped or highest at the edge of the spiral and descending on

a substantially curved line to a lower plane at the base or core of the anchor. This affords an exposed but confining channel for the oil in which it spreads as it flows downward and is heated and ultimately atomized and absorbed by the steam, so that when it reaches the cylinders it is so thoroughly incorporated with the steam that it uniformly coats or covers the cylinder walls and penetrates all the working parts with which the steam comes in contact and lubricates the same in a most effective manner without waste of oil.

50 The spiral may be of any desired length and be covered with wire gauze or mesh 10 as herein shown or without such covering if preferred, depending on conditions in each 55 individual case.

55 In any event the flow of the oil is measured practically in drops, so that the orifice 7 may be very small so far as the flow of the requisite amount of oil is concerned and the 70 control of flow is primarily in the lubricator *b* by suitably disposed valves.

60 What we claim is:

65 1. As a new article of manufacture and sale, an atomizer having a cylindrical body 75 with a spiral channel about the same deepest inside to carry the oil and having a receptacle at its top provided with an orifice in its bottom opening into said channel.

70 2. A steam pipe and an atomizer therein 80 having a spiral channel about the same deepest at the bottom of the channel to convey oil therein and to promote atomization, said atomizer having a tubular neck provided with an escape orifice in its bottom into said 85 channel, in combination with a lubricator and pipe connections therefrom with the said neck.

75 In testimony whereof we affix our signatures in presence of two witnesses.

FRANK B. FRETTER.
STARLEY F. BEASLEY.

Witnesses:

WILL. C. RUETZ,
A. E. MALM.
